UNITED STATES PATENT OFFICE.

ROWLAND FORSTER, OF DAUPHIN, MANITOBA, CANADA.

BAG HOLDER.

1,419,244.

Specification of Letters Patent. Patented June 13, 1922.

Application filed June 1, 1920. Serial No. 385,759.

To all whom it may concern:

Be it known that I, ROWLAND FORSTER, of the town of Dauphin, in the Province of Manitoba, Canada, have invented certain new and useful Improvements in Bag Holders, of which the following is the specification.

The invention relates to improvements in bag holders and the general object of the invention is to provide a device which will receive a bag and hold it with the mouth spread open, thereby making the operation of filling the bag an easy one.

A further object of the invention is to arrange the holder so that it will accommodate the bag as it is filled, that is to say, a holder which will allow the bag to gradually drop under the weight of the grain and as the bag fills.

20 A further object is to provide a bag holder which can be adjusted to accommodate various lengths of bags.

A still further object of the invention is to construct the appliance in a simple, durable 25 and efficient manner.

With the above more important objects in view the invention consists essentially in the arrangement and construction of parts hereinafter more particularly described and 30 later pointed out in the appended claims, reference being had to the accompanying drawing in which:—

Fig. 1 is a front view of the complete device.

35 Fig. 2 is a side view of the same.

Fig. 3 is a plan view.

Fig. 4 is a vertical sectional view through the upper part of the post, certain parts being shown in side elevation.

40 Fig. 5 is a sectional view through one of the spreaders.

Fig. 6 is a perspective view of the carriage plate.

In the drawing like characters of reference indicate corresponding parts in the several figures.

1 represents an upright post or standard in the present instance in the nature of a pipe, the bottom end of which is fitted with 50 a base or such like 2 which can be suitably screwed or nailed to the floor to hold the device permanently in position.

3 is a vertically disposed guide rod spaced from and secured to the front side of the

post and utilized as a sliding support for a 55 carriage later disclosed.

In the present instance the lower end of the rod is bent at right angles to the body and is passed through the post and riveted whilst the upper end is carried by an eye 4 60 fitted with a riveted shank 5 also passing through the post. An angle bracket 6 is secured to the rear side of the post at the point where the shank is riveted.

The carriage 7 is specially constructed, 65 being formed from a metallic plate 8 fitted at the corners with pairs of rearwardly extending upper and lower corner lugs 9 and 10 and centrally with a pair of forwardly extending upper and lower lugs 11 and 12. 70

The body of the plate takes a position between the rod and the post and the forwardly extending lugs 11 and 12 are slidably mounted on the rod whilst the rearwardly extending pairs of lugs are positioned immediately to the sides of the post and serve amongst other functions to prevent a rotary action of the carriage on the rod as would otherwise occur. 75

The carriage is supported by a chain or 80 such like 13 which has the lower end connected to the lug 11 and the upper end detachably connected to the forward end of a rocking lever 14 pivotally mounted on a pivot pin 15 located at the upper end of the 85 post. The rear end of the rocker lever is connected by means of a coiled spring 16 to the bracket 6.

From the above arrangement it will be 90 apparent that the weight of the carriage is carried by the spring which expands and contracts in accordance with the weight of the carriage and bag carried thereby.

In the present instance I have shown a hook 17 at the front end of the rocking lever. One can shorten or lengthen the chain by catching one or other of the links thereof on the hook and in so doing set the carriage to comply with the type of bag used, whether it be long or short. 95

18 and 19 are two forwardly extending bowed arms which arms have their rear ends downturned to provide supporting spindles 20, the spindles being rotatably mounted in the corner lugs of the plate. 100 105

On each spindle and between the corner lugs I mount a coiled spring 21, each spring having one end anchored to the plate and the

other end tied to the spindle and being arranged such that the spring has a constant tendency to spread the arms apart, the spreading action of the arms being limited 5 by stops 22 extending upwardly from the upper lugs 9.

The forward ends of the arms carry curved spreaders 23 and 24, such being in the form of substantially rectangular bowed 10 plates and with each plate having the upper edge bent outwardly as indicated at 25.

When this device is to be used the chain is adjusted as experience teaches to accommodate the length of bag used and when 15 one wishes to place the bag in the holder he closes in the spreaders and passes the hem of the bag over the turned-out edge of the spreader and then releases the spreaders to move out under the action of the springs 21.

20 Actually the body parts of the spreaders are outside the open mouth of the bag as the hem is, so to speak, caught over the turned-out edge of the spreader in each instance. Once in place the mouth of the bag is held 25 fully open by the spreaders and as the bag fills with grain the weight of the grain gradually causes the carriage to move down, such being provided for by the spring 16.

From the above disclosure it will be apparent 30 that this device is very simple in construction and is arranged such that it will accommodate the various lengths of

bags and such that it will adjust itself automatically to the bag as the bag fills with grain.

35

What I claim as my invention is:—

1. A bag holder comprising an upright supporting post, a bag supporting carriage 40 slideable vertically on said post, a rocking lever pivotally secured to said post in a location above said carriage, an adjustable connection extending between said carriage and lever and secured to the latter at one side of the pivot thereof, and a contractible spring on the opposite side of the said post from 45 said adjustable connection, and connected to said lever and said post.

2. A bag holder, comprising a standard, a carriage adjustable thereon, means connected with said standard and carriage for 50 preventing rotation of said carriage, bag holding means on said carriage, a pivoted lever on said standard, an adjustable connection between one end of said lever and said bag holding means, and spring means connected with the other end of said lever for holding said bag holding means in yielding 55 position.

Signed at Dauphin, this 8th day of April, 1920.

ROWLAND FORSTER.

In the presence of—

E. H. GURTON,
E. C. TURLAND.
